COMBINED HOUSING AND HANDLE FOR A PNEUMATIC MOTOR OR THE LIKE

Herbert A. Plassman, Wauseon, Ohio, assignor to The
Aro Equipment Corporation, Bryan, Ohio, a corpora-
tion of Ohio

Application August 6, 1956, Serial No. 42,499

Term of patent 14 years

(Cl. D54—14)

Fig. 1 is a side elevational view of a combined housing and handle for a pneumatic motor or the like showing my new design, the reverse side thereof being substantially similar to the side illustrated.

Fig. 2 is a front elevational view thereof;

Fig. 3 is a horizontal sectional view on the line 3—3 of Fig. 1; and

Figs. 4 and 5 are vertical sectional views on the lines 4—4 and 5—5 respectively on Fig. 1.

The dominant features of my design reside in the portions of the combined housing and handle shown in solid lines.

I claim:

The ornamental design for a combined housing and handle for a pneumatic motor or the like, substantially as shown and described.
